UNITED STATES PATENT OFFICE.

EMANUEL L. CRUM, OF INDIANAPOLIS, INDIANA.

HOOD LATCH.

Application filed July 18, 1925. Serial No. 44,488.

To all whom it may concern:

Be it known that I, EMANUEL L. CRUM, a citizen of the United States, and a resident of Indianapolis, county of Marion, and 5 State of Indiana, have invented a certain new and useful Hood Latch; and I do hereby declare that the following is a full, clear, and exact description thereof, reference being had to the accompanying drawings, in 10 which like numerals refer to like parts.

This invention pertains to a hood latch particularly adapted for use in connection with latching and securing the hoods of automobiles, and is an improvement over the 15 structure shown in Letters Patent No. 1,416,453 issued May 16, 1922.

One feature of the invention resides in the means for adjusting the latch longitudinally thereof, whereby it may be lengthened or 20 shortened by simply rotating the barrel to a length which will exert the proper spring tension for firmly holding the hood in closed position. This is accomplished in a new and improved manner over that shown in 25 the above mentioned Letters Patent in a still more simple and economical structure as will be hereinafter more fully set forth and described.

Another feature of the invention resides 30 in the provision of a bifurcated side clamping member associated with the hood latch in such a manner as to apply lateral pressure in addition to that applied through the medium of the head or fulcrum lever. 35 Whereas it has heretofore been the practice to employ a single laterally projecting member for applying the lateral pressure, such member has permitted wabbling and weaving of the hood and latch, resulting in a 40 cracking sound which is just as annoying as the rattle which it was intended to overcome. By means of this arrangement, the pressure is equally applied at two points in spaced relation so as to firmly hold the hood in 45 place and prevent the wabbling or weaving thereof or any other noise producing displacement.

Another feature of the invention resides 50 in the anchor for the stem of the latch which permits said stem to have free play, at the same time holding it firmly in place and permitting of its easy attachment or detachment from the vehicle.

The full nature of the invention will be 55 understood from the accompanying draw-

ings and the following description and claims.

Fig. 1 is a front elevation showing a hood latch of the usual character without the side members. Fig. 2 is the same as Fig. 1 60 showing a side elevation thereof. Fig. 3 is the same as Fig. 1 showing a side elevation with the hood latch disconnected. Fig. 4 is an enlarged view showing a vertical section through the barrel of the latch and the 65 anchor therefor. Fig. 5 is a section taken on the line 5—5 of Fig. 4. Fig. 6 is a section taken on the line 6—6 of Fig. 4. Fig. 7 is a modified form showing a side elevation of 70 the latch having a barrel structure as illustrated in Fig. 4 and provided with side pressure members. Fig. 8 is the same as Fig. 7 showing a front elevation thereof.

In the drawings there is illustrated in 75 Figs. 1 to 6 inclusive what may be the frame 10 of an automobile and a portion of the hood 11 to be latched or secured thereto. The hood latch comprises a stem 12 which is square or rectangular in cross section as shown in Fig. 5, said stem being provided at 80 its lower end with laterally extending anchor pins 13 which are enclosed and held in place by the anchor plate 14. Said anchor plate is provided with a flange portion adapted to be secured to the frame 10 and having 85 an upwardly extending rounded portion 15 formed with a slot 16 through which the stem 12 may freely pass. The portion 15 of the opening or slot therein is sufficiently 90 large to permit the free movement of the stem with respect thereto, but prevent its being pulled upwardly so as to become disengaged. It will be obvious that upon removing the anchor plate 14 from the frame 10, 95 the stem may be readily removed therefrom but otherwise it will be held against disengagement although being permitted to move freely in any direction. This provides against wear or tearing out the anchor member which is sometimes the case with the 100 usual structure.

The body of the latch comprises the hollow barrel 17 having bifurcated arms 18 extending upwardly from the closed end thereof. The lower end is open and the barrel is internally screw-threaded. Slidably mounted on the stem 12 there is an external screw-threaded disc 19 having a square or rectangular opening to correspond with the shape of the stem whereby it will be non- 110

rotatable with respect thereto, although slideable thereon. The upper end of the stem is provided with a cap 20 rigidly secured thereto so that the compression spring 21 may 5 be mounted intermediate said cap and disc 19 about said stem. By means of this arrangement, upon the stem and barrel being pulled up when the latch is applied, the disc 19 being in engagement therewith, will also 10 be pulled up against the spring 21 so as to compress said spring against the cap 20. Thus a spring tension is exerted for permitting the latching of the hood. Wherein it is desired to vary the length of the latch so 15 as to vary the compression of the spring or permit adjustment for various other reasons, it is only necessary to turn the barrel about the stem which is held by the anchor 14. The disc 19 being likewise held 20 against rotation will be caused to screw up or down within the barrel so as to vary its relative longitudinal position with respect thereto and thus increase or decrease the length of the latch as a whole.

25   Mounted between the bifurcated arms 18 of the hood latch there is a latch head comprising the portion 21 adapted to engage the keeper 22 which is rigidly secured to the hood, and a loop handle 23 extending above 30 the fulcrum point which is at 24. By reason of the arrangement of said parts with respect to each other, it will be noted as shown in Fig. 3, that when the handle portion 23 is pulled away from the hood, the 35 spring tension will be relieved and the portion 21 may be readily disengaged from the keeper 22. On the other hand, upon engaging the portion 21 with the keeper 22, forcing the handle 23 toward the hood, the 40 fulcrum point 24 will pass over dead center and the tension of the spring will create both a downward and lateral pull upon the latching head whereby it will not only exert a down pressure on the hood, but the handle 45 portion will engage the hood and exert a lateral pressure thereagainst as fully set forth and described in the Letters Patent above referred to.

With respect to Figs. 7 and 8, the structure is identical with that above described 50 with the exception that the anchor member 115 is provided with two laterally and rear-

wardly extending arms 25. Said arms also extend rearwardly into engagement with the hood 11 at a point slightly above the bottom thereof and at an appreciable distance below the keeper 22. However in this instance the anchor 115, instead of being rigidly secured to the frame of the vehicle, has formed thereon rearwardly extending 55 ears 116 which embrace an upwardly extending projection 117 pivotally connected with the anchor plate 119. It will be noted that the arms 25 extend at an appreciable distance laterally so that their hood engaging 60 ends are spaced apart sufficiently to apply lateral pressure at two distinct and spaced points on the hood, the pressure at both points being equalized and affected through the upward pull of the stem 12 by reason of 65 the pivotal mounting through the anchor plate 118. Such equalized and widely dispersed pressure will accordingly tend to eliminate wobbling or weaving of the hood and accordingly secures it more firmly in 70 place.

The invention claimed is:

1. A hood latch comprising a hollow barrel provided with internal screw threads, a stem adapted to extend therein, a cap on one 80 end of said stem, an adjusting disc provided with external screw threads adapted to screw in said barrel whereby its position longitudinally thereof may be adjusted by its rotation, said disc being provided with 85 an opening through which said stem slidably but non-rotatably extends, and a compression spring mounted intermediate said disc and cap.

2. A hood latch comprising a hollow barrel provided with internal screw threads, a stem rectangular in cross section adapted to extend therein, a cap secured to the free end of said stem, an exteriorly threaded disc adapted to engage and screw in said first 95 mentioned screw threads having a rectangular opening through which said stem extends whereby said disc will be slidably but non-rotatably associated therewith, and a compression spring mounted about said stem between 100 said disc and cap.

In witness whereof, I have hereunto affixed my signature.

EMANUEL L. CRUM.
